UNITED STATES PATENT OFFICE.

GEORGE W. MAXWELL, OF SAN FRANCISCO, CALIFORNIA.

PAPER RECEPTACLE.

No. 902,754.

Specification of Letters Patent.

Patented Nov. 3, 1908.

Application filed September 23, 1907. Serial No. 394,134.

To all whom it may concern:

Be it known that I, GEORGE W. MAXWELL, a citizen of the United States, residing at San Francisco, in the county of San Francisco and State of California, have invented certain new and useful Improvements in Paper Receptacles, of which the following is a specification.

My invention relates to receptacles made 10 of paper or similar fibrous flexible material, and which are more especially intended for containing liquid or semi-liquid contents, although adapted to the reception of dry products as well.

15 In its especial relation to some kinds of solid and liquid contents, the object of the invention is to provide a receptacle of such character and construction that any seepage of the contents through the walls can be prevented, as well as exterior discoloration, defacement of labels when used, and the giving off of odors from odorous contents.

Another object is the providing of a simple cheap and thoroughly liquid tight 25 containing vessel.

A receptacle constructed according to my invention, has an open ended tubular body formed by wrapping or winding a blank of proper length with a plurality of turns upon 30 a mandrel, the walls of such body thus having a plurality of thicknesses. The body is also formed with special reference to the insertion and liquid-tight securing of bottom and cover disks, and the whole construction 35 results in a simple, cheap, air-tight and liquid tight paper receptacle.

An embodiment of my invention is herein-after described, and is shown in the accompanying drawing, in which:

40 Figure 1 is an elevation, broken to show a vertical section of one end. Fig. 2 is an end view of the receptacle body showing its appearance before it is beaded and crimped, and is also equivalent to a cross section of the 45 body at any plane between its ends. Fig. 3 is a cross section of one of the end disks.

The body 1 of the receptacle is formed from a blank of paper or like fibrous flexible material of suitable thickness, and which is 50 of such length that when wrapped around a forming mandrel at least two complete turns will be required to produce the open-ended tubular structure shown. The body, thus formed, has therefore at least two complete 55 closely fitting thicknesses of material, with its free ends overlapping but separated by

material intermediate between them, as shown at 2, 3, and 4 in Fig. 2.

In order to make a smooth interior joint and uniform inner circumference, the inner 60 free end of the blank is beveled or otherwise reduced to an edge as shown at 5; and although it is not considered necessary in practice, the outer end can also be reduced in like manner so as to make a smooth exterior joint. The parts 2 and 3, and the parts 4 and 5 are secured together by adhesive material between them, and the receptacle is rendered waterproof by a coating 65 of paraffin applied to the inside after 70 the body has been formed.

At each end the body of the receptacle is flared outwardly as shown at 6, and is then turned over or crimped upon the end disk 7. A cross section of one of these disks is 75 shown in Fig. 3. It has a beveled edge which when it is inserted bears with a wedging action against the inner flared surface of the receptacle body, for its own full thickness; and when held in place by the crimping 80 of the receptacle body provides a practically non-leakable joint. I can however, in order to still further guard against the possibility of leakage, coat the beveled edges of the disks with paraffin or with some 85 proper adhesive composition. To guard against accidental displacement of the disks by rough usage, as in shipping for example, and to form a more durable air-tight receptacle, I prefer to place a thick narrow layer 90 of waterproof adhesive material over the seam between the top of the disks and the crimped portion at 6, thus cementing the crimped portion of the disks.

A receptacle constructed according to my 95 invention possesses certain special advantages in addition to the ordinary advantages pertaining to the stiff, practically unbreakable and liquid-tight structure described. When the receptacle contains either solid or 100 liquid contents to which a paraffin coating is not impermeable, such as lard and coal-oil, an ordinary single-walled paper vessel permits a seepage by capillary action which is 105 evidenced by discoloration of the outside of the vessel and of any labels which it may bear, as well as by the odor of such contents. This tends to impair the salability of packages of that character, and to prevent 110 the use of paper receptacles for such substances. With a vessel of double thickness it is possible to coat so much of the blank

as forms the outer surface of the first lap, and which is indicated by the line beginning at x and terminating at y in Fig. 2 with some substance preferably waterproof, and 5 impenetrable by the particular contents, such substance being entirely concealed between adjacent surfaces of the double thickness. This coating therefore never comes into contact with the actual contents of the 10 receptacle, and at the same time effectively prevents such contents from seeping through and discoloring the outside. As the contents are protected from actual contact with such coating by one whole thickness of the 15 body, and as there is another between it and the exterior, it is possible to use for such purpose substances which might ordinarily

be considered objectionable by reason of their odor or from other causes.

What I claim is:

20 In a receptacle of fibrous material, a tubular body made in one piece with a double wall, and having its ends flared and crimped, and bevel-edged closing disks seated on the flared portions and held in position by the 25 crimped portion.

In testimony whereof I have hereunto affixed my signature in the presence of witnesses, on this 11th day of September 1907.

GEORGE W. MAXWELL.

Witnesses:

L. G. MAXWELL,
F. M. BARTEL.
